HERMAN BISCHOFF, OF NEW YORK, N. Y., ASSIGNOR TO DEFIANCE BUTTON MACHINE CO., OF NEW YORK, N. Y., A CORPORATION OF NEW YORK.

PLAITING-MACHINE.

1,345,474.

Specification of Letters Patent.

Patented July 6, 1920.

Application filed December 24, 1917. Serial No. 208,553.

To all whom it may concern:

Be it known that I, HERMAN BISCHOFF, a citizen of the United States, residing at the city of New York, borough of Manhattan, county and State of New York, have invented 5 a certain new and useful Plaiting-Machine, of which the following is a specification.

This invention is a plaiting machine, and 10 the object is, primarily, to conduct in one and the same structure the operations required to be performed on fabrics to produce thereon plaiting known as "side plaits" and as "accordion" plaits, such different 15 kinds of plaiting being attained by a simple adjustment of parts and without in any way changing or altering the construction of the one machine.

The invention relates to means for effecting 20 the control of the plaiting knife and of the fabric feed from and by the operation of a single device, the control of which devices is independent of the automatic movement imparted thereto from and by the 25 drive shaft.

The invention further pertains to the provision of means for effecting a variation in the extent of movement of the plaiting knife so as to produce side plaits of different 30 widths, and, also, of means operable at the same time to effect a variation in the angular distance of rotation of the fabric feed rolls, the variation in the stroke of which plaiting knife and the variation in the angular distance of rotation of said feed rolls 35 being effected, preferably, by the movement of said single manually-operated control member.

The invention pertains also to the provision 40 of means independent of the aforesaid devices whereby the feed of the fabric may be changed to produce accordion plaiting wherein the folds are equal in length, the automatic operation of the plaiting 45 knife and of the feed rolls being otherwise unchanged.

The invention pertains also to the provision 50 of means for feeding the plaiting knife under cam pressure, and to effect its return under spring pressure without dragging the knife in contact with the fabric during such return stroke, whereby thin delicate fabrics 55 may be plaited to the same advantage as other fabrics, and, further, the machine is adapted for operation upon a plurality of layers of

material, such, *e. g.*, as a layer of fabric and one or more layers of other material such as paper, to the end that the fabric may be plaited without injury from the reciprocating knife or the heated roll or rolls, or 60 without imparting a glossy surface to the fabric while passing through the machine, and the layer or layers of paper may remain in contact with the plaited fabric upon removal from the machine so that the plaited 65 paper will assist in retaining the plaits in the fabric during the period of time intervening between removal from the machine and the utilization of the plaited fabric in garment making, or for other purposes. 70

The invention relates further to the provision of means for effecting the operation of the feed rolls independently of the automatic drive in order to advance the fabric without plaiting it, such advance being 75 for regulatable intervals, in order to space apart the plaited portions of the fabric; also, in the provision of means for shifting one feed roll into spaced relation to the other feed roll so as to release the fabric 80 or materials from roll pressure; and, finally, in a simple and efficient construction and organization of parts whereby friction is minimized on the working or moving parts and economy of manufacture is secured. 85

Other features and advantages of the invention will appear in the course of the following detailed description taken in connection with the drawings, wherein—

Figure 1 is a side elevation looking at the 90 machine toward the right in Fig. 3.

Fig. 2 is a side elevation, partly in section, looking at the machine toward the left in Fig. 3, the plane of the section being indicated by the dotted line 2—2 of Fig. 3. 95

Fig. 3 is a plan view of the machine.

Fig. 4 is an enlarged vertical sectional elevation, the plane of the section being indicated by the dotted line 4—4 of Fig. 3 looking in the direction of the arrow. 100

Fig. 5 is an enlarged vertical section illustrating a part of the drive shaft and the shiftable double eccentric on one end portion of said shaft.

Fig. 6 is a detail cross section on the line 105 6—6 of Fig. 5.

Fig. 7 is an end view of the shiftable double eccentric.

The working parts of the machine are supported in the main by two end frames 110

10, 11, said frames being substantially duplicates, and each provided with depending legs 12 and with upright arms 13 which are spaced in parallel order so as to afford 5 guideways for the sliding bearings 14 of an upper pressure roll 15, said roll 15 being one of a pair of coöperating rolls, the other roll of which pair is a heatable roll, indicated at 16, as will be hereinafter more 10 particularly described. The end frames 10, 11 are formed with appropriate bearings for certain rockshafts 17, 18 and for a drive shaft 19. The end frames carry a table 20 positioned on one side of the machine and 15 extended to form a front plate 21, said table 20 being slightly inclined, as shown in Fig. 4, and having an inclined edge portion 22 extending up to or into actual contact with the heatable roll 16. On the other side of 20 the machine the end frames 10, 11 carry an inclined plate 23, the lower portion of which is curved to form a pocket 24 into which the plaited material is adapted to accumulate, the upper end portion of the plate 23 having 25 a lip 25 positioned into close relation to the peripheral surface of the heatable roll 16, see Fig. 4.

The end frames 10, 11 are provided at the bottoms of the guideways formed by the 30 parallel arms 13 with bearings 26, one of which is shown quite clearly in Fig. 2, said bearings receiving the journals 27 provided on the end portions of the lower heatable roll 16. Each journal 27 is a casting separate 35 from the body of the hollow roll 16, said casting forming the journal for supporting an end portion of the roll and the bearing, and said casting being provided with a series of air inlet openings 28, where- 40 by the two hollow journals at the opposite ends of the hollow roll provide an ample supply of atmospheric air to the interior of the roll for the purpose of supporting the combustion of the gaseous fuel by a 45 Bunsen burner 29. Said ample supply of atmospheric air is obtained by openings of large diameter in the hollow journals 27 at the ends of the roll and by the number of air inlets 28 provided in said journals 50 at the respective ends of said roll, whereby the Bunsen burner is adapted to consume gaseous fuel, the combustion being aided by the ample supply of air, so that the roll will be heated by the combustion of gaseous fuel 55 without emitting a perceptible odor, and dispensing with the smoke stack or chimney usually employed in machines of this character for carrying off the noxious fumes due to imperfect combustion.

60 The Bunsen burner consists of a horizontal tube supported in a fixed position within the hollow roll 16, said burner tube 29 being provided with a plurality of upwardly facing slots 30, one of which is 65 shown in Fig. 4. An end portion of this

burner tube extends beyond one side of the machine so as to receive a mixing tube 31 provided with a plurality of air inlets, one of which is indicated at 32 in Fig. 3, and into this mixing tube extends a gas nozzle 70 33 provided on an end portion of a gas feed pipe 34 having a cock 35, whereby gas under pressure is fed to the nozzle 33 so as to become mixed with air supplied through the ports 32, the resulting combustible mixture 75 flowing through burner tube 29 and being ignited at the flame apertures 30 thereof, an ample supply of atmospheric air flowing through the roll 16 and the air ports 28 so as to support combustion of the gaseous fuel. 80

The rockshaft 17 is mounted in suitable bearings provided below the heatable roll, said rockshaft extending the length of the machine. To the end portions of the rockshaft are secured two vibratory arms, one at 85 each end, said arms being indicated at 36, 37. The arms 36, 37 extend upwardly from the rockshaft and carry the plaiting blade 38, the vibratory movement of the arms imparting a reciprocatory movement to the plaiting blade. The plaiting blade is shown as a flat plate of metal provided with slits 40 and with slots 41, the slotted portion of the plate being clamped adjustably by screws 42 to a rocking bar 43 which is mounted for 90 pivotal movement in the upper end portions of the arms 36, 37, whereby the plaiting blade is capable of reciprocatory movement relatively to the heatable roll 16, and it is pivotally mounted in the arms for rocking 100 movement therein in order that said plaiting blade may be depressed by a positive motion into contact with the material to be operated upon during the effective stroke of the blade, whereas upon the return stroke of 105 the blade it is lifted by spring pressure or a tension device so as to be free from contact with said material upon and during said return stroke so as to prevent the blade during 110 the return movement from dragging into contact with the material.

Reciprocatory motion is given to the blade 38 by an eccentric or cam 44 secured to the right-hand end portion of drive shaft 19. The eccentric is embraced by a strap 45 115 forming a part of a link 46, the latter extending from the shaft 19 toward the arm 36, said arm being provided with a longitudinal slot 47 in which is positioned a pin 48. Said pin affords a pivotal connection 120 between the cam-driven link 46 and the slotted vibratory arm 36, so that the motion of eccentric 44 and link 46 operate to automatically impart the vibratory motion to the slotted arm 36, which through the rockshaft 17 imparts motion to the other vibratory arm 37, which arms 36, 37 impart the reciprocatory motion to the plaiting blade 38. The pivotal pin 48 is shiftable in the slot 47 of the arm 36 relatively to the axis 130

of motion of the vibratory arms, and this pin 48 is moved by the operation of a controlling lever 50. The lever is a curved or bent piece attached rigidly to an end portion of rockshaft 18 which serves as a fulcrum for said lever, the latter being extended so as to produce a lever arm 50^a, to the free end of which is pivoted a link 51, the other end of which link is loosely connected with the shiftable pin 48. Movement of the lever in one direction operates the link 51 so as to draw the pivotal stud 48 toward the axis of movement of the vibratory arms, thereby increasing the stroke of the plaiting blade, but it is apparent that the lever 50 can be shifted in an opposite direction for the purpose of moving the pivotal pin 48 away from the axis of movement of the arms 36, 37, thereby decreasing the stroke of the plaiting blade, such variation in the stroke of the plaiting blade being effected by a manual adjustment of the parts, whereas the cam 44 and shaft 19 impart automatic movement to the plaiting blade. The lever 50 is adapted to be fixed in either one of several adjusted positions so as to retain the shiftable pin 48 against accidental movement in the slot of the arm 36 when the cam imparts automatic movement to the plaiting blade. As shown, the lever 50 is positioned into contact with a gage plate 52 fixedly secured to one of the frames 10, said gage plate being provided with a longitudinal slot 53, through which passes a bolt 54 adapted to hold the lever 50 in the desired adjusted position. The plate 52 is graduated, as shown in Fig. 2, so as to determine the position of the lever 50 according to the character of the side plaits to be formed in the material by the movement of the plaiting blade 38.

I will now proceed to describe the means for imparting movement automatically to the heatable roll 16 for the purpose of feeding the plaited material from the table 20 to the inclined plate or table 23, the extent of angular movement of said roll being variable in accordance with the variable stroke of the plaiting blade 38, and such variable movement being imparted to the roll 16 simultaneously with the variable movement given to the plaiting blade 38, all being controlled by the lever 50.

The roll 16 at the end opposite to the Bunnen mixer 31 is provided with a wheel 55, the diameter of which is considerably in excess of the roll, and the periphery of which is formed with a multiplicity of fine ratchet teeth 56, the number of ratchet teeth in my machine being largely in excess of the teeth on ratchets of other machines of which I have knowledge. The ratchet wheel is secured rigidly to the journal 27 at one end of the roll, and loosely sleeved upon this journal is a lever arm 57 the position of

which is indicated by dotted lines in Fig. 1, said lever arm being provided with a strap, indicated in dotted lines at 58, which is loosely fitted around the journal or around the hub of the ratchet, whereby the lever arm 57 is capable of vibratory movement around the axis of a ratchet wheel 55. The lever arm 57 is provided with a stud or pin 59 on which is supported a feed pawl 60, said feed pawl being held by a spring 61 normally into engagement with one tooth of the ratchet wheel 55. The pin 59 is fitted loosely in a slot 62 of an upright segment 63, which lies alongside of the ratchet wheel 55, and to the upper end of this segment is pivoted a driving link 64 provided at one end with a strap 65 which is fitted loosely around an eccentric 66, the construction of which is illustrated more particularly in Figs. 5, 6 and 7 of the drawings. Said eccentric is provided with a stud 67, the axis of the latter being at one side of the axis of the eccentric, see Fig. 7. Said stud enters a socket 68 of a cam head 69, the latter being secured rigidly to an end portion of the drive shaft 19 so as to rotate therewith. The head is provided with binding screw 70 which is tapped into the threaded opening of the head and is adapted for frictional contact with the stud 67, whereby the stud 67 and the eccentric 66 are clamped rigidly to the head 69 for rotation with the shaft 19. It is apparent that the shaft 19 and head 69 impart rotary motion to the eccentric 66 because the latter is clamped by the screw 70 rigidly to the head, and said cam acts through the strap 65 and link 64, to impart vibratory motion to the segment 63, the lower end of which is pivotally supported by a bolt 71 attached to the free end of a rocker arm 72 which is clamped by a screw 73 upon an end portion of the rockshaft 18, to which is attached the controlling lever 50. Said bolt 71 constitutes the axis of movement of segment 63, the vibratory motion of which under the action of cam 66 operates on pivotal bolt 59 to impart movement to the pawl 60 and pawl-carrying arm 57, the latter turning freely on the hub of the ratchet with said ratchet and roll 16 as the axis of movement of said arm 57, whereby the pawl 60 in engagement with a tooth of the ratchet operates to impart intermittent rotative movement to the ratchet and to roll 16. This motion is automatic under the action of means operated by the eccentric 66, but the extent of rotation (angle of movement) of the ratchet and the roll 16 are capable of variation by adjustment, first, of the segment 63 and the eccentric 66. Said segment 63 is controllable by the movement of lever 50 which rocks the shaft 18 and lever arm 72 so as to raise or lower the segment relatively to the pawl pivot 59 so as to vary the

distance between the pawl pivot and the axis of movement (bolt 71) of the segment, thus making provision for effecting a variation in the throw of the pawl and the movement of the ratchet, it being possible to rotate the ratchet by movement of the segment so as to feed it a distance equivalent to two, three, four or more teeth according to the width of the side plait. With the lever 50 held in its first position and with the segment in a predetermined position, the operator can disconnect strap 65 from eccentric 66, thus obtaining access to said eccentric in order to release the screw 70, whereby the operator is enabled to rotate the stud 67 in the socket 68 for a predetermined distance, for the purpose of changing the relation of the eccentric 66 to the cam head 69. The extent of the rotative adjustment of the eccentric to the cam head is according to the width of the folds in the accordion plaiting, and the position of the eccentric to the cam head is indicated to the operator by an index disk 75, which turns loosely on the stud 67, said disk being connected to the eccentric by a pin 76 on the disk fitting in a hole 77 of the eccentric (see Figs. 5 to 7 inclusive), and said disk having a pointer 78 projecting beyond the peripheral edge of the eccentric so as to traverse suitable marks on the cam head. After adjusting the eccentric, the screw 70 is tightened and the eccentric strap 65 is replaced on the eccentric so that the latter will act through the driving link 64 in automatically operating the segment 63 for actuating the pawl and ratchet so as to rotate the feed roll 16.

Said feed roll 16 is provided with a gear 79 (see dotted lines in Fig. 1), with which meshes a gear 80 on the coöperating feed roll 15, said gears operating to transmit the rotative movement of roll 16 to the companion roll 15 for the purpose of feeding the fabric between the rolls, at which time the heat and pressure of the rolls operate to flatten and "set" the plaits in the fabric.

The rocking bar 43 by which the plaiting knife 38 is mounted on the vibratory arms 36, 37 is capable of a back and forth motion with said arms so as to impart reciprocatory movement to the plaiting blade, but this rocking bar and the plaiting blade are capable of independent pivotal movement in order that said blade may on its effective plaiting stroke be positively depressed under cam pressure into contact with the material or materials, whereby the blade is positively actuated so as to plait the fabric and one or more layers of paper. The cam head 69 is provided with a cam surface 81, the contour of which is indicated by dotted lines in Figs. 1 and 6, upon which cam surface rides a friction roll 82 mounted loosely on an end portion of a

rocker arm 83, the latter being pivoted by a bolt 84 to a short arm 85 attached to the rockshaft 18, thus making provision for shifting under the control of lever 50 the relation of the roller 82 and arm 83 to the cam surface 81 on the cam head 69. The rocking bar 43 of said plaiting blade 38 is provided at one end with a finger 86 the free end of which rides upon a friction roller 87 loosely supported on the lever arm 83, and as the surface 81 of the rotary cam head changes position the lever arm 83 and finger 86 are actuated by the cam so as to rock the bar 43 and blade 38 in a manner to depress the same under cam pressure during the forward stroke of blade 38 in effecting the plaiting of the material or materials. It will be noted that lever 83 engages by roller 82 with the cam, and that finger 86 engages a roller 87 on the lever arm, thus reducing to a minimum the friction and wear on the surfaces of the cam 81 and on the parts 83, 86. Upon the reverse movement of the blade 38, a spring 88 acts to rock the bar 43 and lift the blade free from contact with the material, thus precluding the edge of the blade from dragging over the fabric.

The upper roll 15 is pressed by a tension device into contact with the lower roll 16, said upper roll may be solid as shown in Fig. 4 or it may be a hollow roll like lower roll 16. The upper roll is shown as having a fabric cover 89. The sliding bearings 14 of the upper roll are shown as having lugs 90, to which are pivoted at 91 the pressure levers 92, the latter being fulcrumed at 93 on members 13 of the end frames 10, 11. The free ends of levers 92 are engaged adjustably by threaded rods 94 of springs 95, thus making provision for applying spring pressure to the upper roll, the tension of the springs being capable of regulation by adjusting suitable nuts 96^a on the rods 94, see Figs. 1 and 2.

For the purpose of lifting the upper roll 15 from contact with the lower roll, I provide a yoke 96, the arms of which are pivoted at 97 to the tension levers 92, said yoke having a handle 98 and the arms of the yoke being provided at their ends with studs 99 positioned to ride upon the top portions of the end frames 10, 11. With the yoke in the inclined position of Figs. 1 and 2, the levers 92 are under the tension of the springs 95 to apply pressure to the roll 15, but the operator is able to shift the yoke to the vertical position indicated in dotted lines in Fig. 4, thereby raising the levers 92, the sliding bearings 14 and roll 15, said yoke operating to retain the roll in said raised position.

Means are provided for rotating the rolls 15, 16 independently of the cam-actuated pawl and ratchet feed, so that an unplaited or plain fabric may be fed through and by

110

115

120

125

130

the rolls in order to separate two or more plaited portions of the fabric by one or more unplaited portions of said fabric. To this end, a hand lever 100 is loosely connected by a ring 101 to an end portion of roll 15, see Fig. 1, so that the lever may turn part way around the roll with the latter as the axis of movement of the lever. A feed pawl 102 is pivoted to the lever 100 so that the end of the pawl will take into the teeth of the gear 80 on the roll 15, whereby the operator may work the lever 100 back and forth for the pawl and the gear to impart rotative movement to roll 15. The movement of the lever in one direction is arrested by a stop 103 fixed to segment plate 104 so as to lie in the path of the lever, the movement of which in the other direction is arrested by a shiftable stop 105 that is movable to a desired position in a slot 106 provided in the segment plate 104, whereby the stroke of the lever may be regulated between the two stops 103, 105, see Fig. 1.

The material X to be operated upon is held under tension by guiding and tension means positioned over the table 20 so as to lie closely adjacent to the operating blade 38. Suitable brackets 107 are fastened to the end frames 10, 11, at points close to the sides of the table 20 and intermediate the ends thereof. Said brackets carry rods 108, 109, which extend across the table, and upon these rods are fitted the sliding guides 110, the latter being shiftable at will along the rods so as to correspond to the width of the fabric to be plaited. By adjustment of the sliding plates 110, two or more pieces of narrow fabric may be fed to the rolls and the plaiting blade for conducting the plaiting operation simultaneously on a number of fabrics. Said fabric passes below rod 108 and over rods 109 which act on the fabric so as to keep the required tension thereon. By placing the tension and guide devices over the table and adjacent to the blade 38, the fabric can be kept taut clear to the end of the fabric.

In addition to feeding the fabric to the plaiting blade, means are provided for feeding paper to said blade, one strip of paper Z being shown in Fig. 4 as passing over the table 20 and below the fabric X, but it is apparent that an additional strip (not shown) can be fed over the fabric, whereby one or more strips of paper may be plaited with the fabric by the operation of blade 38. The strip or strips of paper do not pass through the tension device. The underlying paper keeps the fabric from direct contact with the heated roll 16 so as to preclude scorching the fabric, and the overlying paper precludes the rolls from imparting a glossy appearance to the surface of the fabric. By plaiting the paper with the fabric, the paper may be removed with the

fabric from the machine so that the plaited paper will remain attached to the plaited fabric so as to help in keeping the plaits in the fabric until it is desired to use the latter.

The operation is as follows:—Assuming it is desired to produce side plaits in a piece of fabric, which side plaits are quite narrow as shown at X' in Fig. 4, the material X with or without one or more layers of paper Z is positioned over the table 20 and between rolls 15, 16, and thence extended over the inclined plate 23, said material being in the path of the plaiting blade and the fabric X being passed over one guide rod, below the next one, and over the succeeding rod so as to keep the fabric under tension. Before setting the machine into operation, the attendant shifts lever 50 so as to regulate the stroke of the plaiting

blade and to regulate, also, the rotative feed of the roll 16, the eccentric 66 being in the position of Fig. 1. The drive shaft is operated for rotating cams 44 and double cam 66, 69 as a result of which the driving link 46 imparts the desired stroke to the blade 38, the driving link 64 operates segment 63 for actuating the pawl and ratchet so as to rotate the feed rolls, and the lever arm is lifted by the cam head so as to depress the blade 38 upon the effective stroke thereof.

The fabric is thus plaited and the plaited fabric fed by the rolls, the head of which tends to set the plaits, the plaited fabric passing down the plate 23 into the pocket. The fabric is fed under tension, either alone or in conjunction with one or more layers of paper. The operation is continued as long as desired and without change of parts to produce plaits of a desired width and overlap in the fabric.

Should it be desired to decrease the width of the plait or the overlap thereof, then the lever 50 is moved in one direction and held in such position by the screw bolt, the effect of which movement is to shift the pin 48 and to shift the segment 63 at one and the same operation, thus changing the stroke of the blade 38 and changing also the extent of rotative movement of the feed

roll 16 upon the subsequent operation of the machine by the cams 44, 66; but should it be desired to increase the plait or the overlap thereof, then the lever 50 is moved in an opposite direction, thus reversing the adjustment of parts 48, 63 so as to correspondingly affect the plaiting blade 38 and the feed roll 16.

For producing accordion plaiting in the fabric, the lever 50 is adjusted to a position wherein the blade 38 is moved the desired distance, but the member 66 of the double cam 66, 69 is shifted by releasing screw 70 and changing the cam member 66 relatively to the head 69, the index disk being movable

- with the cam member 66 to the desired position, after which the screw 70 is tightened and the parts restored to operating positions. Now when the shaft 19 is rotated, the several parts of the machine are operated as before, but the cam member 66 operates the segment and pawl so as to feed the fabric one tooth of the ratchet at a time, so that there is a uniform feed of the fabric to produce the accordion plaiting, the width of the plaits being variable by adjustment of lever 50 which controls the operating devices for the plaiting blade and the feed roll.
- 15 The lever arm 83 controlled by the rock shaft 18 acts to bring the two cams 44, 66, on the power shaft into synchronism, whereby the changes in the depression and lifting motion of the plaiting blade and in the feed and speed motion of the rollers are brought into unison, which motion requires one setting of the lever 50 instead of independent adjustment of the pins 48, 59. It is apparent that the shifting of the pivotal pin 48 in the slotted arm 36 results also in a shifting of the pivotal connection 59 in the slotted segment 63, but this change leaves the relation of the cams 44, 66, unchanged and the automatic drive would have a tendency to work out of time; but in my machine, the lever arm 83 is operated from the shaft 18 at the time that the pins 48, 59 are shifted so that the relation of the roller 82 to the cam surface 81 is shifted in order that the cams 44, 66, will operate properly without resetting either of said cams 44, 66.
- 20 Suitable means are provided for imparting rotative movement to the drive shaft 19; as shown, a wheel 111 is attached to the shaft at one end thereof, said wheel being provided with a crank 112 for its operation by hand. The wheel 111 is shown, also, as having a groove adapted to receive a power driven band or belt whereby the wheel may be driven by power, from a suitable source, if desired.
- 25 Having thus fully described my invention, what I claim as new and desire to secure by Letters Patent is:
- 30 1. In a plaiting machine, the combination with a reciprocatory plaiting blade, and material-feeding means, of means for effecting a variation in the stroke of said plaiting blade, means for effecting a variation in the motion of the material-feeding means, and means controllable at will for simultaneously shifting the plaiting blade feed means and the material feed means.
- 35 2. In a plaiting machine, the combination with a reciprocatory plaiting blade, and material feed means, of a single lever controllable at will, a plurality of devices controllable by said lever, one of said devices being effective in varying the stroke of said blade and the other of said devices operating to effect a variation in the feed of said material feed means, and driving means co-operating with said plurality of devices in imparting movement to the plaiting blade and the material feed means.
- 40 3. In a plaiting machine, the combination with a reciprocatory plaiting blade, and material feed means, of driving means for imparting movement simultaneously to said plaiting blade and the material feed means, means separate from the driving means for effecting a variation in the stroke of said plaiting blade, means separate from the driving means for effecting a variation in the feed of said material feed means, and means operable at will and independently of the driving means for shifting the blade-variation means and the feed-variation means simultaneously.
- 45 4. In a plaiting machine, the combination with a reciprocatory plaiting blade, and material feed means, of driving means for imparting movement simultaneously to said plaiting blade and the material feed means, means separate from the driving means for effecting a variation in the stroke of said plaiting blade, means separate from the driving means for effecting a variation in the feed of said material feed means, and means operable at will and independently of the driving means for shifting the blade-variation means and the feed-variation means simultaneously.
- 50 5. In a plaiting machine, the combination with vibratory arms, a plaiting blade, and a drive shaft, of a cam-driven member shiftably connected to one of said vibratory arms, a controlling lever connected for shifting at will the connection of said cam-driven lever relatively to the axis of movement of the vibratory arms, and means for locking said lever in any one of several positions to which said lever may be shifted.
- 55 6. In a plaiting machine, the combination with vibratory arms, one of which is slotted, a plaiting blade carried thereby, and a drive shaft, of a cam-driven link having a pivotal connection with said slotted vibratory arm, and a lever controllable at will for shifting said pivotal connection relatively to the axis of motion of the vibratory arm.
- 60 7. In a plaiting machine, the combination with vibratory arms, a plaiting blade carried thereby, and means for imparting vibratory motion to said arms, of a lever arm shiftable at will, a cam with which contacts said lever arm, and a finger carried by the plaiting blade and contacting with said lever arm whereby the plaiting blade is depressed under cam pressure and provision is made for retaining the parts in a desired relation while other parts of the machine are manipulated.
- 65 8. In a plaiting machine, the combination with vibratory arms, a plaiting blade carried thereby, and means for imparting vibratory motion to said arms, of a driving cam for depressing said plaiting blade, a finger carried by the plaiting blade, a lever arm intervening said driving cam and the

70 75 80 85 90 95 100 105 110 115 120 125 130

finger and contacting therewith, and means for manually shifting the position of said lever arm with respect to the driving cam and said finger.

5 9. In a plaiting machine, the combination with vibratory arms, a plaiting blade carried thereby, and means for imparting vibratory motion to said arms, of a driving cam for depressing said plaiting blade, a 10 finger carried by said plaiting blade, a lever arm provided with a plurality of friction rollers, one of which contacts with said driving cam and the other with said finger, and means for shifting at will the lever arm with 15 respect to the driving cam and the finger.

10 10. In a plaiting machine, the combination with a feed table and feed rolls, of means for placing tension upon a fabric adapted to be moved by said feed rolls over said 20 table, means for directing a material other than fabric to said feed rolls, whereby the last mentioned material is advanced by the feed rolls simultaneously with the fabric, a plaiting blade operable in producing plaits in the fabric and said other material simultaneously, means for imparting reciprocatory motion to the plaiting blade, and means for rotating the feed rolls intermittently.

11. In a plaiting machine, the combination 30 with a feed roll, and a reciprocating plaiting blade, of a ratchet wheel fast with said feed roll, a pawl coöoperating with said ratchet wheel, an arm carrying said pawl, a rockable segment pivotally connected with 35 said arm, cam operated means for imparting vibratory motion to said segment and to the pawl-carrying arm and means for shifting the position of said segment with respect to said pivotal connection between the 40 pawl-carrying arm and the segment.

12. In a plaiting machine, the combination 45 with a feed roll and a reciprocating plaiting blade, of a ratchet wheel fast with said feed roll, a pawl-carrier provided with a pawl coöoperating with the ratchet wheel, a segment having a pivotal connection with 50 said pawl carrier, means operable at will for shifting said segment relatively to the pawl carrier for imparting thereto variable movement whereby the pawl and ratchet are adapted for varying the angular distance of 55 movement of the feed roll, and power operated means for imparting vibratory movement to said segment and the pawl carrier.

55 13. In a plaiting machine, the combination 60 with a feed roll and a reciprocating plaiting blade, of a ratchet fast with said feed roll, a pawl-carrier provided with a pawl coöoperating with the ratchet, a segment connected with said pawl carrier, power-operated means for imparting vibratory motion to said segment and the pawl carrier, and manually-operable means for shifting the 65 segment to vary the distance between the axis of movement of said segment and the

pawl whereby the angular distance of movement of the feed roll is varied at will independently of the automatic motion imparted to the power-operated means.

14. In a plaiting machine, the combination 70 with a reciprocating plaiting blade and a feed roll, of a ratchet fast with said roll, of a segment, power-operated means for rocking said segment, a pawl coöoperating with the ratchet and operated by the movement of 75 the segment, and means for shifting the segment relatively to the pawl so as to vary the distance intermediate the axis of the pawl and the axis of movement of the segment whereby the travel of the pawl and the angular distance of rotation of the feed roll may be varied at will.

15. In a plaiting machine, the combination 80 with a plaiting blade and a feed roll, of a rocking segment, cam-operated means for 85 rocking said segment, a movable member on which the segment is fulcrumed whereby said segment is shiftable at will, and pawl and ratchet mechanism operable by the movement of the segment for rotating the 90 feed roll.

16. In a plaiting machine, the combination 95 with a plaiting blade and a feed roll, of a drive shaft, an eccentric head having a rigid connection with said drive shaft, an eccentric provided with an eccentric pin attached to said eccentric head, said eccentric being rotatable at will on an axis afforded by the eccentric pin so as to vary the relation of the eccentric pin to the drive shaft, pawl and ratchet mechanism coöoperating with the feed roll, and means actuated by the eccentric in either of the adjusted positions thereof for operating the pawl and ratchet mechanism to impart movement to the feed roll, the extent of which movement is adapted to be 100 varied by adjustment of the eccentric. 105

17. In a plaiting machine, the combination 110 with a feed roll and a plaiting blade, of a drive shaft, an eccentric separate from the shaft, said eccentric being provided with an eccentric pin affording an axis of rotation for the adjustment at will of the eccentric relatively to the axis of the drive shaft, means whereby said eccentric may be released and adjusted to different operative positions relatively to the shaft, pawl and ratchet mechanism coöoperating with the feed roll, and means operated by the eccentric for operating the pawl and ratchet 115 mechanism the angular movement of which is regulatable by variation in the relation of said eccentric to the drive shaft. 120

18. In a plaiting machine, the combination 125 with a feed roll, and a plaiting blade, of a drive shaft, a segment, pawl and ratchet mechanism operated by said segment for rotating said feed roll, an eccentric provided with an eccentric pin affording an axis of rotation around which the eccentric is adjust- 130

able at will, means for rigidly and detachably connecting said eccentric with the drive shaft, whereby the eccentric may be rotatably adjusted at will with respect to said shaft; and a driving link pivoted to the segment and operated by said eccentric.

19. In a plaiting machine, the combination with a plaiting blade and a feed roll, of a drive shaft, an eccentric carried thereby and shiftable relatively thereto, means for fixedly attaching said eccentric to the shaft, a driving link operated by said eccentric, a segment pivoted to said driving link, a shifting fulcrum for said segment, pawl and ratchet mechanism operated by the movement of said segment for imparting rotative movement to said feed roll, and means operable at will for shifting the segment and its fulcrum so as to vary the distance intermediate the axis of the segment and the axis of movement of said pawl.

20. In a plaiting machine, the combination with a feed roll, a pivotally mounted plaiting blade, and means for imparting reciprocatory movement to said blade, of a rotative cam, a lever arm having two rollers one of which is in contact with the cam, an arm attached to said blade and contacting with the other of said rollers for depressing the blade under cam pressure during the effective stroke thereof, and means operable at will for shifting said lever arm relatively to said cam.

21. In a plaiting machine, the combination with a feed roll, and a plaiting blade, of a drive shaft, a cam on said shaft, means including a shiftable pivot operated by said cam for imparting reciprocating movement to said blade, a second cam carried by the drive shaft, pawl and ratchet mechanism co-operating with the feed roll, means including a shiftable pivot operated by the second cam for actuating the pawl and ratchet mechanism so as to impart intermittent rotative movement to the feed roll, and means operable at will whereby the two shiftable pivots may be changed so as to effect at one operation a variation in the stroke of the plaiting blade and a variation in the angular distance of rotation of the feed roll.

22. In a plaiting machine, the combination with a pair of co-operating rolls, one of which is hollow, and means for rotating said hollow roll, of means for driving the other roll from said hollow roll, and means operable at will and separate from said driving means for imparting rotative movement to said other roll whereby the material in an unplied condition may be fed through said rolls.

23. In a plaiting machine, the combination with co-operating rolls, and driving means for intermittently rotating said rolls,

of means operable at will and independently of said driving means for imparting rotative movement to one of said rolls whereby unplied material may be fed through said rolls.

24. In a plaiting machine, the combination with co-operating rolls, a plaiting blade, and driving means for intermittently rotating said rolls, of a lever and pawl operable at will and independently of the driving means for rotating said rolls.

25. In a plaiting machine, the combination with co-operating rolls, a plaiting blade, and driving means for intermittently rotating said rolls, of a lever and pawl operable at will and independently of the driving means for rotating said rolls, and means in the path of said lever for arresting the motion thereof whereby the feed rolls may be rotated independently of the driving means for effecting a variation in the feed of unplied material.

26. In a plaiting machine, the combination with a frame, co-operating rolls, and sliding bearings for one of said rolls, of spring actuated levers connected with said sliding bearings for applying tension to one of said rolls, and a manually operable yoke having pivotal connection with said spring actuated levers, said manually operable yoke being provided at its end portions with projections positioned for contact with the frame and operable in retaining the slidible roll in a raised position relatively to the co-operating roll.

27. In a plaiting machine, the combination with a feed roll, and pawl and ratchet mechanism co-operating therewith, of a vibratory member for actuating said pawl and ratchet mechanism, a drive shaft, a cam head on said shaft, an eccentric attached to the cam head and shiftable at will relatively thereto, an index member shiftable with the eccentric and co-operating with the cam head, and a driving link pivoted to said vibratory member and co-operating with said eccentric.

28. In a plaiting machine, the combination with feed rolls, a pivoted reciprocatory plaiting blade, and an intermittent feed mechanism for said feed rolls, of a drive shaft, a double eccentric thereon each part of said double eccentric being rotatably shiftable at will independently of the other part, means operated by one part of the double eccentric for actuating the intermittent roll feed mechanism, and means actuated by the other part of the double eccentric for imparting pivotal movement to said plaiting blade.

In testimony whereof I have hereunto signed my name.

HERMAN BISCHOFF.
